UNITED STATES PATENT OFFICE.

CARL ROBERT BLUM, OF BERLIN-SCHONEBERG, GERMANY.

REPRODUCTION OF MUSIC IN SYNCHRONISM WITH MOVING PICTURES.

Original application filed January 6, 1923, Serial No. 611,199. Divided and this application filed April 20, 1925. Serial No. 24,839.

To all whom it may concern:

Be it known that I, CARL ROBERT BLUM, a citizen of Germany, residing at Berlin-Schoneberg, Germany, have invented certain new and useful Improvements in Reproduction of Music in Synchronism with Moving Pictures, of which the following is a specification.

My invention relates to the reproduction of pieces of music by any desired means, such as the human voice, musical instruments, piano players, gramophones, phonographs, and the like in synchronism with the moving pictures reproduced by a cinematograph, and it is an object of my invention to warrant a reproduction in that particular rhythm which is peculiar to each individual piece of music. Only military and other marches and many dances have a uniform rhythm and all times are reproduced in the same measure. With all other pieces of music, however, the tempo changes more or less often, frequently in the single consecutive times, and even within single bars. This very change of tempo is a material characteristic feature of such pieces of music. Their reproduction corresponds to the intention of the composer perfectly only if not only all tones, but also all rhythmic variations are reproduced in the most exact manner.

To warrant a rhythmically exact reproduction of all sung and played pieces of music in synchronism with the moving pictures reproduced by a cinematograph, I make use of the following means:

1. A band which is unwound from one reel and wound upon another reel and has the music piece written or printed upon it in the usual notes and in uninterrupted succession, in such a manner that the distance between the notes of each single bar and the length of the space occupied by each bar upon the band (with relation to the speed with which the band is moved when a record is made or a recorded piece of music is reproduced) corresponds to the speed with which these notes or bars are to be reproduced.

2. A stationary mark past which the band passes and which indicates to the singer or player or conductor the proper moment at which each note or bar is to be reproduced.

3. Means to wind the band upon the reel

and to unwind it from the same, and to make it travel past the stationary mark either with uniform or with varying speed, but always with just that speed with which the band had been traveling when the record was made.

4. Means to couple the band or its operating mechanism with a cinematographic apparatus for taking pictures or for reproducing them, and with means for obtaining synchronous running of the music band and the film.

In the drawings affixed to this specification and forming part thereof several devices embodying my invention are illustrated diagrammatically by way of example. In the drawings

Fig. 1 is a perspective view of the note band itself with its two reels.

Fig. 2 is a like view of the means for causing the band to travel past the stationary mark, and of means for adjusting the traveling speed of the band in conformity with the general character of the piece of music to be played.

Figs. 3 to 10 are illustrations of means for electrically coupling the note band mechanism with a cinematographic apparatus, in such a manner that the note band and the film move synchronously,

Fig. 3 being an elevation, the front wall of the box being left away,

Fig. 4 a plan of the parts located in the upper compartment of the casing, the lid being left away,

Fig. 5 a horizontal section on the line IX-IX in Fig. 3 showing the parts located in the lower compartment of the casing.

Fig. 6 is a perspective view of the device illustrated in Figs. 3 to 5, as applied to a grand piano and electrically connected with a cinematographic apparatus.

Fig. 7 is a front view of the frontal parts of the cinematographic apparatus showing more particularly some of the means for obtaining synchronism of the note band and the film.

Figs. 8 and 9 are a longitudinal and a cross section, respectively, drawn to a larger scale, of part of the mechanism shown at the right hand side of the middle portion of Fig. 7.

Fig. 10 is a front view of the other part of this mechanism.

Fig. 11 is a diagrammatic view of an apparatus in which the note band and the film are combined.

Referring to the drawings, the note band 1 separately illustrated in Fig. 1 consists of a strip of durable material, such as cardboard, celluloid, linen, or the like, and has its ends wound upon reels 2 and 3. The band has one or several staffs 4 the single bars of which are not of equal length nor of any desired length, but whose length is determined by the tempo in which they are to be played. Thus, of several bars of a piece of music that which is to be played with an accelerated tempo (accelerando) occupies a shorter space than a bar that is to be played at a slower tempo (ritardo). The notes are spaced apart within the single bar in such a manner that as the band is traveling along, each note is made to travel past a stationary mark at that very moment at which it is to be played or sung. Such a mark 5 (Fig. 2) is arranged for instance in the middle of a frame 6, having an oblong slot across which the band is made to travel.

If the band is moved solely by the rotation of the reel 2 which pulls it through the frame 6, the bars obtain other lengths and the notes are placed at other distances during the inscribing of the notes, that is while making the record, than if the band is uniformly moved past the mark. This is due to the increase of the diameter of the reel, while the band is wound on it, in consequence of which the speed of the band permanently increases. It is, therefore, preferable, instead of pulling the band, to employ a uniformly rotating device which engages the band between the reels, as shown for instance in Figs. 3-9.

In the modification shown in Fig. 2 a clock work 9 can be wound up by means of a crank 7 and bevel wheels 8; the clock work rotates by means of gear wheels 10 and 11, the spindle 12 of the reel 2 in the direction of the arrow. The reel 2 winds up the band 1 which comes from the reel 3 and passes over guide rolls 13, as well as through the frame 6.

The singer, player, or orchestra-leader, sitting in front of the apparatus, has to pay attention solely to the moment at which the various consecutive notes arrive at the mark 5 when the respective note is to be produced. The general tempo of the respective piece of music is adjusted in correspondence with the tempo regulations prescribed in the given case and followed either with the aid of Mälzel's metronome or of some other time beating device, the adjustment being effected by means of a regulating device 14 (Fig. 2) which cooperates with a scale 15 and influences the speed of the band, for instance by braking or by changing the ratio of gearing.

Figs. 3 to 10 relate to modifications in which the traveling note band is combined and electrically coupled with cinematographic apparatus in such a manner that the film on the stage or other room and the note band in the auditorium move at the same speed although being distanced apart from each other.

Irrespective of whether a piece of music is to be recorded or to be reproduced, the band 1 is actuated indirectly by the film mechanism which in its turn is operated, as usual, either by hand or by means of a motor. The crank 20 (Fig. 6) rotates the shutter spindle 21 to which is affixed a pinion 22 rotating the spindle 26 of a rotary switch 27 by means of a gearing 23, 24, 25. The spindle 26 has attached to it an arm 28 to which is secured a sliding commutator brush 29 which, during the rotation of the arm, consecutively glides across contacts 30, 31 and 32 located in groups of four in the corners of a quadrangle and being conductively connected with each other so that, if one contact of a group of four is touched, also the other three of that group are thrown into circuit. The contacts of the rotary switch are connected by a four-wire cable with a small magneto-electric machine 34 which drives the actuating device of the note band 1.

This machine (Figs. 3, 5 and 10) consists of a spider 36 affixed to a spindle 35 and capable of turning in the same direction above twelve magnet coils 37 arranged in a circle around said spindle. Rotation in the opposite direction is prevented by a ratchet wheel 38 secured to the spindle 35 and cooperating with a pawl 39. Groups of four coils 37 also located in the corners of a quadrangle are conductively connected with each other and with a group of four contacts of the circular switch 27. When the brush 29 touches a contact, the magnets connected with the respective group of contacts and forming part of the machine 34 are excited and attract the arms 36. On the continued rotation of the brush 28 the next following group of contacts is thrown into circuit and in its turn throws in the next following group of magnets which now attracts the spider 36. The rotation of the brush lever therefore results in the excitation of the magnet groups, attraction of the spider and rotation of the spindle 35 in synchronism with the spindle 26 of the switch 27 and in the same direction and with the same speed. The note band 1 and the film are therefore fed along in dependence upon the ratio of gearing of the intercalated cog-wheel gear, either with exactly the same speed or with an exactly proportionate one, but always in exact synchronism. If the ratio of gearing is suitably chosen, the note band may, for instance, be moved with but one tenth of the

speed of the film, and a film of, say, 100 meters may thus be accompanied with a note band of 10 meters.

When reproducing, the reel 41, upon which the film is wound, is rotated by the electro-motor 43 which is connected by a wire 44 with a rheostat 45 located at the note band apparatus and permitting of regulating from a distance the number of revolutions of the motor and, in connection therewith, the adjustment of the desired velocity of the note band by way of the film driving means. The player of the instrument 46 shown in Fig. 6 observes with the aid of a hand 48 in front of a scale 47 whether the basic tempo at which the pictures were taken is kept up during their reproduction and, in connection therewith, also during the travel of the note band, the proper tempo being kept up with the aid of the rheostat.

Inversely, the film drive may be made dependent upon the music band or upon the driving gear thereof in that this gear transmits the motion of the note band to the film by electrical or pneumatic or mechanical means.

It is, however, also possible to make the film and the music band run off jointly in one place and to let the conductor standing near the cinematographic apparatus indicate the rhythm for the taking of the pictures corresponding to the indications or regulations of the note band. Such a combination is illustrated diagrammatically in Fig. 11 where the upper part 60 of the casing encloses the note band 61 which has a middle line of perforations cooperating with a cogged drum 62 operated by the driving mechanism of the cinematographic apparatus housed in the lower part 63 of the casing, so that the conductor watching the note band through a window conducts the orchestra as well as the film actors.

The length of the note band is preferably reduced in a certain definite proportion (for instance 1:10) so that each meter of the band corresponds to 10 meters of film, there being then provided a corresponding transmission gearing between the two driving mechanisms.

The note band and the devices operating in conformity with this invention permit of fulfilling many different purposes.

The note band renders valuable services as a means for teaching music in that it enables the scholar, as well as the instructor or the conductor, to study and reproduce music pieces in exact conformity to the rhythmic instructions of the composer. Besides, in connection with automatic music apparatus, such as for instance gramophones or piano players, the note band renders possible the cooperation of singers or of instrument players in perfect synchronism with the tempo of the piece of music the respective

apparatus is producing, the singers or musicians reading the accompanying music and reproducing it by means of the notes traveling past the mark at the rhythm of the respective music-producing apparatus.

In connection with cinematographic apparatus the note band permits of taking the images in the most exact synchronism with the music, the conductor directing the actors according to the indications of the note band and this latter regulating the feeding of the film, so that the note band and the film run synchronously during the reproduction, and the parts of the musical film which have been recorded synchronously with the rhythm are reproduced also in exact synchronism with the rhythm. On the other hand, the note band may be prepared also according to the rhythm of the finished film and will then warrant exact synchronism of the pictures with the music during the reproduction. The note band may also replace the prompter.

If the note band is provided with contacts, it may control devices (gramophones or the like) which at certain parts of the music or at certain pictures produce noises, such as explosions, whistles, street noise, and the like, corresponding to the respective scenery.

I wish it to be understood that I do not desire to be limited to the exact details of construction or operation described and illustrated in the drawings, for obvious modifications will occur to a person skilled in the art.

This application is a division of application Serial No. 611,199, filed Jan. 6, 1923.

I claim:

1. The combination with a cinematographic apparatus and a photographic film, of a note band provided with a plurality of notes spaced between the consecutive bars thereof to visually indicate the variations in rhythm of sounds associated with said film, a motor for moving said band past a fixed point, and a commutator switch continuously operated by a moving part of said apparatus and controlling said motor.

2. The combination with a cinematographic apparatus and a photographic film, of a note band provided with a plurality of notes spaced between the consecutive bars thereof to visually indicate the variations in rhythm of sounds associated with said film, a motor for moving said band past a fixed point, a commutator switch continuously operated by a moving part of said apparatus and controlling said motor, and means for regulating the speed of said motor by variation in the current supplied thereto.

3. The combination with a cinematographic apparatus, a photographic film and mechanism for moving said film through said apparatus, of an apertured frame, a mark extending across the aperture in said

frame, a note band comprising a plurality of consecutive notes spaced apart in proportion to the variations of rhythm in a piece of music, an electric motor for moving said band at uniform speed through said frame and past said mark, and a rotary switch, controlling the motor field and connected for continuous operation by said film moving mechanism and in circuit for causing said electric motor to transport said band in synchronism with said film.

4. The combination with a cinematographic apparatus and a photographic film, of a note band provided with a plurality of notes spaced to indicate variations in rhythm of sounds associated with said film, a motor for moving said band past a fixed point, and a switch having an arm geared to a moving part of said apparatus and engaging a series of contacts in circuit with said motor for controlling the field thereof.

5. The combination with a cinematographic apparatus and a photographic film, of a note band provided with a plurality of notes spaced to indicate variations in rhythm

of sounds associated with said film, an electro magnetic motor for moving said band past a fixed point and having an armature with radiating arms, and a switch having an arm actuated by a moving part of said apparatus and cooperating with a grouped plurality of contacts in circuit with the motor field controlling the radiating arms of said electro magnetic motor connected to move said band in synchronism with the film. 35

6. The combination with a cinematographic apparatus and a photographic film, of a note band provided with a plurality of notes spaced to indicate variations in rhythm of sounds associated with said film, a motor for moving said band past a fixed point, a switch arm geared to a rotating part of said apparatus and cooperating with an annular series of contacts, and circuit connections therefrom to simultaneously transmit current to a plurality of field contacts to control said motor. 40 45

In testimony whereof I affix my signature.

CARL ROBERT BLUM.
